[57] **CLAIM**

The ornamental design for a socket organizer, as shown and described.

DESCRIPTION

FIG. 1 is a front elevational view of a socket organizer showing my new design;

FIG. 2 is a rear elevational view thereof;

FIG. 3 is a left side elevational view thereof;

FIG. 4 is a right side elevational view thereof;

FIG. 5 is an enlarged top plan view thereof;

FIG. 6 is an enlarged bottom plan view thereof; and,

FIG. 7 is an enlarged horizontal cross-sectional view thereof, taken along line 7—7 of FIG. 1.

The broken-line disclosure of socket sizes in FIGS. 3 and 4 is for illustrative purposes only and forms no part of the claimed design.
